UNITED STATES PATENT OFFICE.

JOHN W. BUCHANAN AND CLARENCE S. BUCHANAN, OF FOLKSTON, GEORGIA.

SAP-COLLECTING RECEPTACLE.

Application filed September 17, 1926. Serial No. 136,084.

This invention relates to certain new and useful improvements in sap collecting receptacles of the type adapted to be secured to trees to receive crude turpentine or other sap exuding therefrom and has for its main object to provide an improved sap cup which may be readily secured to and removed from a tree.

Another object of the invention is to provide a sap collecting receptacle of the class described which may be formed from a single piece of sheet metal and which is susceptible of being readily applied to the tree and held thereon in the level position against accidental displacement and which is so formed that the sap may be removed therefrom with facility.

Another object of the invention is to provide a sap receptacle of the character described which is provided with a special shaped opening adapted to receive therethrough a supporting member of such a shape that the receptacle will be maintained in the level position and held in such position against accidental displacement and in which the opening serves also as an overflow opening for the receptacle.

A further object of the invention is to provide a receptacle of the class described which embodies to a marked degree the characteristics of simplicity, durability and efficiency in construction and which is well adapted for quantity production at comparatively low cost.

Further and more limited objects of the invention will appear as the description proceeds and by reference to the accompanying drawing in which Fig. 1 is a perspective view of our improved sap collecting receptacle with the reinforcing member secured in place; Fig. 2 is a view similar to Fig. 1 showing the receptacle before the seam has been formed; Fig. 3 is a horizontal sectional view on the line 3—3 of Fig. 1; Fig. 4 is a detail perspective view of the reinforcing member; Fig. 5 is a detail perspective view of the supporting member for the receptacle and Fig. 6 is a view showing the blank from which the receptacle is formed.

Our improved receptacle is constructed from a blank of sheet metal 1 shown most clearly in Fig. 1. The metal is bent to form a semi-circular front wall 2 and a flat back wall 3. The back wall has a seam 4 extending longitudinally thereof which is formed by bending the metal back upon itself as dis-

closed most clearly in Fig. 3. Extending through the seam at a point adjacent the upper end thereof is an irregular shaped opening 5 which is preferably in the form of a keyhole slot as disclosed in Fig. 1. This opening 5 is adapted to receive a special shaped supporting member 6 shaped as shown most clearly in Fig. 5. The receptacle is adapted to be supported by the supporting member 6 which extends through the opening 5 and the opening serves also as an overflow opening for the receptacle. In Fig. 4 there is disclosed a reinforcing member 7 which is also preferably formed from a blank of sheet metal and shaped as shown most clearly in Fig. 4. This reinforcing member 7 is adapted to be secured to the straight side 3 of the receptacle by any suitable means as by welding. As will be seen in Fig. 1 this member engages on each side of the seam 4 and tends to reinforce the straight back side of the receptacle.

It will now be clear that the receptacle can be secured over the supporting member only when the receptacle is in level position and due to the special shape of the opening 5 and the supporting member 6 the receptacle will be retained in the level position. The receptacle can be readily removed from the supporting member for the purpose of emptying the sap when necessary. It will be impossible to secure the receptacle to the tree except in the correct position. The opening 5 is large enough so that the supporting member does not obstruct the water from flowing out of the cup below the supporting member 6.

It will now be clear that we have provided a sap collecting receptacle which accomplishes the objects of the invention as hereinbefore stated and we wish our invention to be limited only in accordance with the scope of the appended claims.

Having thus described our invention, what we claim is:

1. A sap collecting receptacle adapted to be secured to the body of a tree and comprising a cup formed from a blank of sheet metal bent to form a curved front wall and a flat back wall, the back wall having a seam extending longitudinally thereof and having a longitudinally extending irregular shaped opening therein disposed adjacent the upper end thereof and serving as an overflow for said cup, said opening adapted to receive a complementary shaped support.

- ing member therethrough whereby to support said cup in the level position and of sufficient size to serve as an overflow for said cup and a reinforcing member formed 5 from a blank of sheet metal and secured to said back wall on opposite sides of said seam whereby to reinforce said back wall and to prevent said opening from being torn out.
- 10 2. A sap collecting receptacle comprising a single piece of material bent to form a cone shaped cup the front wall of which is curved and the back wall of which is flat and provided with a longitudinally extending
- 15 seam therein formed by bending the opposite edges of the piece of material back upon itself, the said seam having a vertically

extending irregular shaped opening therein near the upper edge thereof adapted to receive therethrough a complementary shaped supporting member, the bottom edge of said opening lying below the bottom edge of said supporting member whereby to permit said opening to serve as an overflow for said cup and a reinforcing member secured to 20 said back wall on opposite sides of said seam whereby to reinforce said back wall and to prevent said opening from being torn out.

In testimony whereof, we hereunto affix 25 our signatures.

JOHN W. BUCHANAN.
CLARENCE S. BUCHANAN.
